SLIDING DOOR LOCK

John A. Buzard, Glendale, Calif., assignor to Adams Rite Manufacturing Company, Glendale, Calif., a corporation of California

Filed Oct. 14, 1963, Ser. No. 76,962

Term of patent 14 years

(Cl. D50—5)

FIG. 1 is a front elevational view of a sliding door lock showing my new design;

FIG. 2 is a back elevational view of the same;

FIG. 3 is a side view as seen from the left in FIG. 1;

FIG. 4 is an opposite side view;

FIG. 5 is a top view;

FIG. 6 is a bottom view;

FIG. 7 is a perspective view; and

FIG. 8 is a transverse section of the same, taken substantially on line 8-8 of FIG. 2.

I claim:

The ornamental design for a sliding door lock, as shown.
